H. E. DILLON,

CONCRETE PIPE CONSTRUCTION.
APPLICATION FILED JUNE 16, 1919.

1,351,895.

Patented Sept. 7, 1920.

INVENTOR:

HARRY EDGAR DILLON,

By Arthur E. Paige,
Attorney.

UNITED STATES PATENT OFFICE.

HARRY EDGAR DILLON, OF PHILADELPHIA, PENNSYLVANIA.

CONCRETE PIPE CONSTRUCTION.

1,351,895.

Specification of Letters Patent.

Patented Sept. 7, 1920.

Application filed June 16, 1919. Serial No. 304,418.

To all whom it may concern:

Be it known that I, HARRY EDGAR DILLON, a citizen of the United States, residing at Philadelphia, in the county of Philadelphia and State of Pennsylvania, have invented a certain new and useful Improvement in Concrete Pipe Construction, whereof the following is a specification, reference being had to the accompanying drawing.

10 The principal purpose and effect of my invention is to join primarily separate elements of concrete or similar compositions, in monolithic relation, so as to permit such elements to be precast or molded remote 15 from the region in which they are to be assembled, and facilitate their assemblage, by ordinary tools, and unskilled labor, in such relation that the joints between them may be rendered permanently fluid tight.

20 My invention may be advantageously employed in the production of water mains and sewers, but it may be embodied in other structures, regardless of whether the elements thereof are cylindrically or otherwise 25 curved, or flat.

My invention includes the various novel features of construction and arrangement hereinafter more definitely specified.

In the drawing; Figure I is a fragmentary perspective view of a cylindrical reinforced concrete conduit embodying my invention.

Fig. II is a fragmentary perspective view of a reinforced concrete conduit of U-shaped cross section, embodying my invention.

Fig. III is a fragmentary perspective view of a flat composition slab, such as is employed in the formation of the upper wall of the conduit shown in Fig. II.

Fig. IV is a fragmentary plan view of a structure embodying my invention, at a joint between complementary primarily separate elements thereof.

Fig. V is a fragmentary sectional view of the complete joint contemplated in Fig. IV.

Fig. VI is a fragmentary perspective view showing means for connecting, in accordance with my invention, a cradle and a saddle such as shown in Fig. I, and the conduit and its cover slab shown in Fig. II.

Fig. VII is a fragmentary perspective view of one of the interlocking wedge hoops such as may be employed in each of the two joints of the conduits shown in Fig. I.

Fig. VIII is a fragmentary perspective

view of one of the interlocking wedge bars shown in Fig. II.

Referring to Fig. I: The similar precast reinforced cylindrical tubular concrete sections 1, 1 have each of their opposite ends 60 tapered, preferably in concavely curved form, as indicated at 2 in Fig. V; so that when abutted, as indicated in the latter figure, they form a circumferential channel for the receptacle of a plastic material, such 65 as concrete or similar composition 3, sealing the joint between them.

Each of said conduit sections 1 is provided at its ends with means to interlock with the adjoining sections; such means being, preferably, metallic rods 5, which not only have their ends 6 outwardly turned beyond the ends of the plastic composition of said section, but said rods are preferably extended longitudinally through the entire 75 length of the section from which they project, so as to reinforce the plastic material in which they are embedded. Of course, said sections 1 may be additionally reinforced by expanded metal or other foraminous material, either exterior to said rods 5, as indicated at 7 in Fig. V, or within the circular series of said rods as indicated at 8 in said figure.

As best shown in Fig. V; the rod ends 6 85 are inclined outwardly from the sections 1 in which they are respectively embedded, so that when said ends are overlapped, they form between them an inwardly converging seat for an interlocking wedge bar 9, which 90 is preferably wedge shaped in cross section, with its thinner edge presented inwardly, as shown in Fig. V. As shown in Fig. VII, said bar 9 may be a circular hoop having hooked ends 11, so that it may be drawn 95 around the joint, and locked in the seat between said rod ends 6, and thus exert sufficient tensile strain upon said rods 5, to draw said conduit sections 1, 1 together, in rigid relation. I prefer to embrace each 100 pair of rod ends 6 with a primarily loose coupling link 10, to stiffen the joint aforesaid.

Moreover, I find it convenient to protect and reinforce each joint between the conduit sections 1, by a bonding element, which may be precast as a single annular piece 12, as indicated in Figs. I and V, or may be precast in complementary parts as indicated at 13 and 14 in Fig. I. The part 13 forms 105 110

a cradle, which rests upon the ground 15 and upholds the conduit section 1 therefrom, as indicated, and the part 14 is a saddle which, when interlocked with said cradle, as 5 hereinafter described, retains said sections 1 in rigid monolithic relation with said bonding element.

10 Preliminary to the formation of the joint between the abutting sections 1, 1, shown in Fig. V, said unitary bonding element 12 may be slipped over one of them and retained at such distance from the joint as not to interfere with the manipulation of the wedging elements aforesaid. However,

15 15 when said interlocking wedge bar has been inserted, as indicated in Fig. V, said bonding ring 12 may be slipped longitudinally upon the conduit section 1 until it is located centrally over the joint, as shown in Fig.

20 20 V. Thereupon, liquid concrete, or other suitable sealing composition 3, may be poured through the inlet openings 16 in said ring 12, into the concavely curved channel 18, which has been precast in said ring,

25 25 and which is complementary to the circumferential channel formed by the concavely curved ends 2 of said sections 1. Such sealing means, flowing entirely around the conduit sections 1 and filling the interstices between said sections and said ring unites them in monolithic relation and renders the joint aforesaid fluid tight.

30

35 In the form of my invention shown in Fig. II; the conduit is formed of sections which are not only primarily separate longitudinally; but each of said sections is formed of two parts which are primarily separate transversely. The lower part 20 of said conduit is U-shaped in cross section and the upper part 21 is a flat slab or series 40 of slabs. Said conduit member 20 may have reinforcing rod 23 with outwardly turned ends 24, like the rods 5 above described, and said conduit member 21 may have similar 45 reinforcing rods 26 with outwardly turned ends 27; said rod ends 24 and 27 being adapted to overlap in their projection from abutting sections a conduit and to be interlocked by suitable wedge bars, substantially 50 as above described. However, I find it desirable to further reinforce the slab with cross bars 28 having hook ends 29 adapted to project in longitudinal channels 31 in the plastic portion of the conduit section 20 in 55 which they may be cemented by liquid concrete or other suitable plastic material poured through the inlets 32 which extend through said slabs 21 in registry with said channels 31. Moreover, said hook ends 28 60 may interlock with metallic loop or eye bars 34, embedded in the opposed element of the conduit, as indicated in Fig. VI.

It is to be understood that the connecting means shown in Fig. VI, may be employed to interlock, in monolithic relation, the pri-

marily separate complementary bonding elements 13 and 14 shown in Fig. I.

Furthermore, I may provide interlocking wedge bars 36, for adjoining slabs 21, each of said bars having projecting ends 37, as shown in Figs. II and VIII, which are fitted to be embedded in said channels 31 when in the wedging position shown in Fig. II.

11. Although it is unnecessary, I find that it 75 facilitates the assembling of the metallic rods 5 to encircle them with annular bands 39, disposed at intervals throughout the length of the conduit section 1 in which said rods are embedded and each conveniently 80 formed of a cylindrical rod flattened at its ends, or a strip of sheet metal, having its ends connected by an ordinary nail 40 thrust through registered openings therein and bent. Although said bands may be connected to said rods by wire ties twisted around the bands where the rods cross them; I prefer to provide said bands with recesses 41, conveniently by bending said bands, so that said rods may be engaged therewith 85 in uniform spaced relation, without tying them with wire as above contemplated. Moreover, the operation of assembling the rods 26 and cross bars 28, in the relation shown in Fig. III, is facilitated by bending 90 them as indicated at 45 and 46 so that they interlock in the desired relation. Of course, such interlocking of the metallic reinforcements of the conduits above described not only facilitates the operation of assembling 95 them but materially increases their resistance to the strains to which the conduits are subjected. 100

I do not desire to limit myself to the precise details of construction and arrangement herein set forth, as it is obvious that various modifications may be made therein without departing from the essential features of my invention, as defined in the appended claims. 105

I claim:

1. The combination with a tubular member adapted to form a unit section of a pipe, formed of a non-metallic composition and having its opposite ends tapered to less diameter than its body; of longitudinal reinforcing means including members embedded in said body and projecting outwardly at the ends thereof in obliquely transverse relation to the axis of said body, but terminating within the perimeter of said body; another similar tubular section having one end abutting one end of said first section; the projecting ends of the reinforcing members of the respective sections laterally overlapping in the direction of the length of the structure and forming wedge seats between them; metallic coupling links, each encircling adjoining ends of said reinforcing members of the respective tubular sections, a wedge member, including a bar of wedge 115
120
125
130

shaped cross section, having its thin edge extending inwardly in said seats, and forming a hoop substantially concentric with the axis of said structure; said wedge bar exerting tensile strain upon said reinforcing members to hold said tubular sections together, and the tapered ends of said sections forming a circumferential channel in which the coupled ends of said reinforcing members extend; a bonding element, adapted to encircle the joint between said sections, having an internal channel complementary to the channel formed by the abutting ends of said sections, and having inlet openings through it, in registry with said channel, to receive liquid sealing means to fill said channel; said bonding element including two parts which are primarily separate transversely with respect to the axis of said structure; a reinforcing device for said bonding element, including a bar in one part thereof having its ends projecting substantially parallel with the axis of said structure in recesses in the other part of said bonding element, in engagement with reinforcing eye bars in the latter; and sealing means poured into said channel through said inlets and uniting and retaining the elements of said structure in monolithic relation.

ed to form a unit section of a pipe, and having an end tapered to less area than its body; of reinforcing members embedded in said body and projecting outwardly at the ends thereof in obliquely transverse relation to the axis of said body; another similar section having its tapered end abutting the tapered end of said first section; the projecting ends of the reinforcing members of the respective sections overlapping in the direction of the length of the structure; a wedge member, including a bar of wedge shaped cross section, having its thin edge extending inwardly between said overlapped ends and exerting tensile strain upon said reinforcing members to hold said tubular sections together; the tapered ends of said sections forming a channel in which the ends of said reinforcing members extend; a bonding element, adapted to cover the joint between said sections, having an internal channel complementary to the channel formed by the abutting ends of said sections, and having an inlet opening adapted to receive sealing means to fill said channel; and sealing means extending into said channel through said inlet and uniting and retaining the elements of said structure in monolithic relation.

2. The combination with a member adapted to form a unit section of a pipe, and having an end tapered to less area than its body; of reinforcing members embedded in said body and projecting outwardly at the ends thereof in obliquely transverse relation to the axis of said body; another similar section having its tapered end abutting the tapered end of said first section; the projecting ends of the reinforcing members of the respective sections overlapping in the direction of the length of the structure and forming wedge seats between them; metallic coupling links, each encircling adjoining ends of said reinforcing members of the respective tubular sections; a wedge member, including a bar of wedge shaped cross section, having its thin edge extending inwardly between said overlapped ends, and forming a hoop substantially concentric with the axis of said structure; said wedge bar exerting tensile strain upon said reinforcing members to hold said tubular sections together, and the tapered ends of said sections forming a circumferential channel in which the coupled ends of said reinforcing members extend; and sealing means in said channel, forming a liquid tight joint between said sections.

3. The combination with a member adapted to form a unit section of a pipe, and having an end tapered to less area than its body; of reinforcing members embedded in said body and projecting outwardly at the ends thereof in obliquely transverse relation to the axis of said body; another similar section having its tapered end abutting the tapered end of said first section; the projecting ends of the reinforcing members of the respective sections overlapping in the direction of the length of the structure; a wedge member, including a bar of wedge shaped cross section, having its thin edge extending inwardly between said overlapped ends and exerting tensile strain upon said reinforcing members to hold said tubular sections together; the tapered ends of said sections forming a channel in which the ends of said reinforcing members extend; a bonding element, adapted to cover the joint between said sections, having an internal channel complementary to the channel formed by the abutting ends of said sections, and having an inlet opening adapted to receive sealing means to fill said channel; and sealing means extending into said channel through said inlet and uniting and retaining the elements of said structure in monolithic relation.

4. The combination with a tubular member adapted to form a unit section of a pipe, formed of a non-metallic composition and having its opposite ends tapered to less diameter than its body; of reinforcing members embedded in said body and projecting outwardly at the ends thereof in transverse relation to the axis of said body; another tubular section having one end abutting one end of said first section; the projecting ends of the reinforcing members of the respective sections overlapping in the direction of the length of the structure and forming wedge seats between them; metallic coupling links, each encircling adjoining ends of said reinforcing members of the respective tubular sections; a wedge member, including a bar of wedge shaped cross section, having its thin edge extending inwardly between said overlapped ends, and forming a hoop substantially concentric with the axis of said structure; said wedge bar exerting tensile strain upon said reinforcing members to hold said tubular sections together, and the tapered ends of said sections forming a circumferential channel in which the coupled ends of said reinforcing members extend; and sealing means in said channel, forming a liquid tight joint between said sections.

5. The combination with a tubular member adapted to form a unit section of a pipe, formed of a non-metallic composition and having its opposite ends tapered to less diameter than its body; of reinforcing members embedded in said body and projecting

outwardly at the ends thereof in transverse relation to the axis of said body; another tubular section having one end abutting one end of said first section; the projecting ends 5 of the reinforcing members of the respective sections overlapping in the direction of the length of the structure; a wedge member, including a bar of wedge shaped cross section, having its thin edge extending inwardly between said overlapped ends, and forming a hoop substantially concentric with the axis of said structure; said wedge bar exerting tensile strain upon said reinforcing members to hold said tubular sections together, and the tapered ends of said sections forming a circumferential channel in which the coupled ends of said reinforcing members extend; and sealing means in said channel, forming a liquid tight joint 20 between said sections.

6. The combination with a hollow body having one end tapered; of members projecting outwardly at said end thereof in transverse relation to the axis of said body; another such hollow body having similar members; the projecting ends of said members of the respective bodies overlapping in the direction of the length of the structure and forming wedge seats between them, and 25 said tapered ends forming a channel; metallic coupling links, each encircling adjoining ends of said members of the respective bodies; a wedge member, including a bar of wedge shaped cross section, having its thin edge extending inwardly between said overlapped ends, and forming a hoop substantially concentric with the axis of said structure; said wedge bar exerting tensile strain upon said members to hold said bodies together, and sealing means in said channel embedding the interlocked portions of 30 said members and forming a liquid tight joint between said bodies.

7. The combination with a nonmetallic body; of reinforcing members embedded in said body and projecting outwardly at the end thereof; another similar body; the pro-

jecting ends of the reinforcing members of the respective bodies overlapping in the direction of the length of the structure and 50 forming wedge seats between them; metallic coupling links, each encircling adjoining ends of said reinforcing members of the respective bodies; a wedge member, including a bar of wedge shaped cross section, 55 having its thin edge extending inwardly between said overlapped ends; said wedge bar exerting tensile strain upon said reinforcing members to hold said bodies together; and sealing means forming a liquid tight 60 joint between said bodies.

8. An article of manufacture, adapted for connecting adjoining sections of a pipe, including an annular hoop of wedge shaped cross section having its thin edge extending 65 inwardly; said hoop being formed of a flexible metallic bar having coupling means at its ends rendering said loop capable of sphincteral adjustment.

9. An article of manufacture, adapted for 70 connecting adjoining sections of a pipe, including an annular hoop of wedge-shaped cross section having respectively thick and thin edges upon radially opposite sides and having its thin edge extending inwardly 75 toward its axis.

10. The combination with two bodies each having a circular series of hooks overlapping the hooks in the other body; of means adapted for drawing said bodies together, 80 including an annular hoop of wedge shaped cross section having respectively thick and thin edges upon radially opposite sides and having its thin edge extending inwardly 85 toward its axis between said overlapped hooks, and means at the ends of said hoop constructed and arranged to constrict it.

In testimony whereof, I have hereunto signed my name at Philadelphia, Pennsylvania, this fourteenth day of June, 1919.

HARRY EDGAR DILLON
